UNITED STATES PATENT OFFICE.

OLIN S. FELLOWS AND ARCHIBALD E. HOPKINS, OF MIDDLETOWN,
NEW YORK.

APPARATUS FOR REMOVING SUPERFLUOUS METALLIC COATING FROM SHEET METAL.

No. 810,851.

Specification of Letters Patent.

Patented Jan. 23, 1906.

Application filed April 28, 1905. Serial No. 257,952.

To all whom it may concern:

Be it known that we, OLIN S. FELLOWS and ARCHIBALD E. HOPKINS, citizens of the United States, residing at Middletown, Orange county, and State of New York, have invented certain new and useful Improvements in Apparatus for Removing Superfluous Metallic Coating from Sheet Metal, of which the following is a specification sufficient to enable others skilled in the art to which the invention appertains to make and use the same.

Our improvements relate to means for removing excess of metallic coating from sheet metal, particularly what is known as "list," from the selvage edges of sheet-metal plates for the purpose of recovering and saving such excess of metallic coating and also for the purpose of rendering the plates more valuable by making the selvage edges available for use.

Our treatment of the plates is supplemental, and after the list or excess of metallic coating has set or hardened on the sheet metal in the ordinary course of the manufacture of commercial plate, as set forth in our applications for Letters Patent, Serial No. 226,441, filed September 29, 1904, and Serial No. 230,994, filed November 1, 1904, to which reference may be had for a general understanding of the state of the art.

The distinguishing feature of our present invention consists, essentially, in manipulating and treating the sheet metal for the removal of the excess of metallic coating while the plates are bent or curved to a prescribed degree for the purpose of rendering them uniform in shape and preventing or counteracting the tendency of the sheet metal to buckle or warp under the heat to which the selvage edges of the plates are subjected in reducing the list or excess of metallic coating to a fluid condition preparatory to its removal.

The invention consists, primarily, in mechanism for bending the plates and feeding them in that position in such manner that their selvage edges are first presented to means for heating the same to melt the metallic excess *in situ* and then to means for removing such liquated excess from the edges of the plates, substantially as hereinafter set forth, and, secondarily, the invention includes certain other features in the construction and arrangement of parts hereinafter described and claimed specifically.

In the accompanying drawings, Figure 1 is

a plan of our apparatus; Fig. 2, a vertical sectional elevation taken upon plane of line 2 2, Fig. 1. Fig. 3 is a front view of the apparatus; Fig. 4, a rear view of the same; Fig. 5, a side elevation; Fig. 6, a sectional elevation upon plane of line 6 6, Fig. 1; Fig. 7, an enlarged view illustrating the removal of the liquated list by means of brushes; Fig. 8, a similar view illustrating the removal of the list by a fluid-blast; Fig. 9, a detail view of one of the tension-levers.

In carrying out our invention practically there are three important essentials—namely, a convexly-curved plate support or feed of uniform radius movable upon the axis of said curve, means concentric to said axis for heating the edge of a plate presented upon said convex feed, and means also concentric to said axis for forcibly removing the liquated excess of metallic coating from the heated edge of the plate.

In order to simplify the apparatus and render the operation continuous, we prefer to use a rotatable drum or cylinder as a support upon which to feed the plates to the devices for heating and removing the list, although this is not indispensable, since it is obvious which the convex feed might be made to reciprocate instead of to rotate, as shown and described herein, would be within the spirit and intent of invention.

In the drawings the stationary framework of the apparatus consists of two side members or standards A A, united by cross-rods a a and by a stationary axle a', upon which latter the sleeve-axle d of the hub D is mounted.

P P P are pulleys attached to shafts p p p, which are mounted in bearings p' p' p', supported adjustably upon the side members A A.

P' represents tension-pulleys mounted loosely upon arms or levers L, fulcrumed on the shaft l and each carrying a weight W to impart the required degree of tension to each of the endless feed-belts B B B, which pass around the drum D and over the said pulleys P P P and P', as will be understood by reference to Fig. 6. The metal plates to be treated are fed in between these endless feed-belts B and the periphery of the drum D, power being applied to a driving-pulley p² on one of the shafts to cause the belts and drum to travel in the directions indicated by the arrows.

Adjoining one peripheral edge of the drum

D and concentric thereto are two gas-burner pipes G G or equivalent means of heating the edge of a sheet-metal plate protruding over said edge of the drum, as illustrated in detail in Figs. 7 and 8. Beyond this heating device is arranged means M for removing the liquated list or excess of metallic coating from the edge of the sheet metal, such means consisting of a pair of rotatable concavo-convex brushes, as shown in Fig. 7, of a fluid-blast, as illustrated in Fig. 8, or of any other suitable expedient that will insure the displacement of the superfluous metallic coating, which may be precipitated into a compartment or conduit C, from which it may be withdrawn in any convenient manner.

From the foregoing the operation of removing list from the selvage edge of sheet metal, as tin from sheet-iron, will be readily understood. A plate h, of so-called "commercial tin," for instance, is fed in between the feeding-belts B and the periphery of the drum D with its selvage edge h' projecting beyond the edge of the drum upon the side upon which the means for melting and removing the list i are situated. The tension maintained upon the feed-belts B causes them to press and hold the body of the sheet-metal plate firmly against the periphery of the drum D, to the surface of which it conforms, its selvage edge protruding concentrically, so that said selvage edge is carried between the gas-jets or equivalent means of imparting the necessary degree of heat to reduce the list or excess of tin to a fluid state, in which condition it is subjected to the means for removing it from the sheet metal.

The curved concentric form of the plate while under treatment counteracts or neutralizes the tendency of the plate to warp or buckle under the heat to which its edge is subjected and insures a true and perfect alinement of position with relation to the list melting and removing means.

It is to be noted that by the use of the endless belts in conjunction with the rotatable drum we attain a flexible means of binding the plates upon the holder, and in this connection the automatic tension is important in that it admits of and compensates for the insertion and removal of plates and also provides for a continuous operation of the parts in one direction. Thus the device may be said to automatically receive the plates and hold them during treatment, discharging them automatically after the removal of the list.

The concentric arrangement of the means for liquating and removing the list with relation to the curved plate-holder is the distinguishing feature of our invention, by means of which we are enabled to attain accurate results, not only by reason of the avoidance of buckling or warping in the plate, but also because a perfect alinement of parts is as-

sured, the edge of each plate treated following the same path and receiving the same treatment.

What we claim as our invention, and desire to secure by Letters Patent, is—

1. In apparatus for removing superfluous metallic coating from sheet metal, the combination of curved plate-feeding mechanism and means concentric thereto for melting and removing the excess of metallic coating from the plate.

2. In apparatus for removing superfluous metallic coating from sheet metal, the combination of convex plate-feeding mechanism and means concentric thereto for melting and removing the excess of metallic coating from the plate.

3. In apparatus for removing superfluous metallic coating from sheet metal, the combination of curved plate-feeding mechanism, flexible means for holding a sheet-metal plate thereto and means concentric to said curved feed mechanism for melting and removing the excess of metallic coating from the plate.

4. In apparatus for removing superfluous metallic coating from sheet metal, the combination of means for bending a plate thereof and means for melting and removing the excess of metallic coating from said plate while so bent.

5. In apparatus for removing superfluous metallic coating from sheet metal, the combination of means for bending a plate of coated sheet metal and means for heating the edge of said plate and removing the list therefrom while the plate is so bent, for the purpose described.

6. In apparatus for removing superfluous metallic coating from sheet metal, the combination of means for bending a plate of coated sheet metal, means for heating said bent metal plate to melt the excess of metallic coating thereon, and means for removing the liquated excess of metallic coating from the plate while the latter is so bent, for the purpose described.

7. In apparatus for removing superfluous metallic coating from sheet metal, the combination of curved plate-feeding mechanism, means concentric thereto for heating an edge of the plate to melt the list or excess of metallic coating thereon, and means, also concentric to the feed mechanism, for removing the liquated excess of metallic coating from the heated edge of the plate for the purpose set forth.

8. In apparatus for removing superfluous metallic coating from sheet metal, the combination of curved plate-feeding mechanism, flexible means for holding a sheet-metal plate thereon, means concentric to said feed mechanism for heating the edge of the plate to melt the list or excess of metallic coating thereon, and means, also concentric to the feed mechanism, for removing the liquated

excess of metallic coating from the heated edge of the plate for the purpose set forth.

9. In apparatus for removing superfluous metallic coating from sheet metal, a curved plate-holder of uniform radius, means concentric to said curved plate-holder adapted to heat an edge of a plate held on said holder and remove the list therefrom, and means for moving said holder to subject the edge of the plate to the action of the list heating and removing means, for the purpose described.

10. In apparatus for removing superfluous metallic coating from sheet metal, a rotatable drum, means for holding a coated sheet-metal plate upon and against the periphery of said drum, and means concentric to said drum for melting and removing list or excess of metallic coating from the edge of a plate so held on said rotatable drum, for the purpose described.

11. In apparatus for removing superfluous metallic coating from sheet metal, a rotatable drum, flexible means for holding a coated sheet-metal plate upon and against the periphery of said drum, and means concentric to said drum for melting and removing list or excess of metallic coating from the edge of a plate so held on said rotatable drum, for the purpose described.

12. In apparatus for removing superfluous metallic coating from sheet metal, a rotatable drum and an endless belt traveling with said drum and arranged to hold a coated sheet-metal plate against the periphery of said drum, and means concentric to said drum for melting and removing list or excess of metallic coating from the edge of a plate so held on said rotatable drum, for the purpose described.

13. In apparatus for removing superfluous metallic coating from sheet metal, a rotatable drum, a plurality of endless belts traveling with said drum and arranged to hold a coated sheet-metal plate against the periphery of said drum, and means concentric to said drum for melting and removing list or excess of metallic coating from the edge of a plate so held on said rotatable drum, for the purpose described.

14. In apparatus for removing superfluous metallic coating from sheet metal, a rotatable drum, an endless belt traveling with said drum and arranged to hold a coated sheet-metal plate against the periphery thereof, means for automatically maintaining the tension of said belt, and means concentric to said drum for melting and removing list or excess of metallic coating from the edge of a plate so held on said rotatable drum, for the purpose described.

15. In apparatus for removing superfluous metallic coating from sheet metal, a rotatable drum, a plurality of endless belts traveling with said drum and arranged to hold a coated sheet-metal plate against the periphery there-

of, means for automatically maintaining the tension of said belts, and means concentric to said drum for melting and removing list or excess of metallic coating from the edge of a plate so held on said rotatable drum, for the purpose described.

16. In apparatus for removing superfluous metallic coating from sheet metal, a curved holder of uniform radius, means for automatically receiving and holding a coated metallic plate upon said curved holder, means concentric to said holder adapted to heat the edge of said metallic plate and remove the list therefrom, and means for moving said holder with relation to the means for melting and removing the list, for the purpose set forth.

17. In apparatus for removing superfluous metallic coating from sheet metal, a rotatable drum, means for automatically receiving and holding a coated sheet-metal plate upon and against the periphery of said drum, and means concentric to said drum for melting and removing list or excess of metallic coating from the edge of a plate so held on said rotatable drum, for the purpose described.

18. In apparatus for removing superfluous metallic coating from sheet metal, a movable curved plate-holder of uniform radius, a series of gas-jets arranged concentric to the path of the holder for the purpose of heating the edge of a plate held thereon, and means, also concentric to the curved plate-holder, arranged to remove the liquated excess of metallic coating from the edge of the plate for the purpose described.

19. In apparatus for removing superfluous metallic coating from sheet metal, a movable curved plate-holder of uniform radius, two series of gas-jets concentric to the path of the holder, one opposed to the other, and arranged to heat opposite sides of the edge of a plate held on said holder, and means also concentric to the curved plate-holder arranged to remove the liquated excess of metallic coating from the edge of the plate for the purpose described.

20. In apparatus for removing superfluous metallic coating from sheet metal, a rotatable drum, means for holding a coated sheet-metal plate against the periphery of said drum, a series of gas-jets arranged concentric to one edge of said drum, for the purpose of heating the edge of a plate held thereon, and means, also concentric to the edge of said drum, arranged to remove the liquated excess of metallic coating from the edge of the plate for the purpose described.

21. In apparatus for removing superfluous metallic coating from sheet metal, a rotatable drum, means for holding a coated sheet-metal plate against the periphery of said drum, two series of gas-jets arranged concentric to one edge of the said drum and opposed to each other for the purpose of heat-

ing opposite sides of the edge of a plate held on said drum, and means, also concentric to the edge of the said drum, arranged to remove the liquated excess of metallic coating 5 from the edge of the plate for the purpose described.

22. In apparatus for removing superfluous metallic coating from sheet metal, a curved plate-holder of uniform radius, means for holding a coated metallic plate thereon, concentric means for heating one of the edges of said plate to melt the list thereon, and rotatable concavo-convex brushes arranged with their opposite sides concentric with the 10 curved plate-holder and in the path of the edge of the plate held thereon, for the purpose described.

23. In apparatus for removing superfluous metallic coating from sheet metal, a rotatable drum, means for holding a coated sheet-metal plate against the periphery of said drum, concentric means for heating one of the edges of said plate to melt the list thereon, and rotatable concavo-convex brushes arranged with their opposed sides concentric with the periphery of the drum and in the path of the edge of the plate held thereon, for the purpose described. 20 25
